(57) **CLAIM**

The ornamental design for a table base as shown and described.

DESCRIPTION

FIG. 1 is a perspective view of a table base showing my new design;

FIG. 2 is a front elevation view thereof;

FIG. 3 is a top plan view thereof;

FIG. 4 is a bottom plan view thereof; and,

FIG. 5 is a perspective view thereof shown in an environment of use as a coffee table.

The broken lines showing in the drawings are for the purpose of illustrating portions of the table base and form no part of the claimed design.
